UNITED STATES PATENT OFFICE.

EDWARD RUSSELL-CLARKE, DECEASED, BY FRANCES MAUD RUSSELL-CLARKE,
EXECUTRIX, OF LONDON, ENGLAND, ASSIGNOR TO AUTOKAL SYNDICATE LIMITED,
OF LONDON, ENGLAND.

CALCULATING MACHINE.

Application filed December 9, 1919. Serial No. 343,631.

To all whom it may concern:

- Be it known that I, Mrs. FRANCES MAUD RUSSELL-CLARKE, a subject of the King of Great Britain, and residing at London, in England, sole executrix of EDWARD RUSSELL-CLARKE, late a subject of the King of Great Britain, who invented certain new and useful Improvements in Calculating Machines, of which the following is a specification.
- 10 This invention relates to calculating machines and has for its object to combine with a typewriting machine a machine capable of performing multiplication and also with or without means for performing addition and subtraction.
- 15 According to this invention a typewriting machine of known construction provided with numeral keys and tabulating keys which serve to determine the position of the paper in the typewriting machine relative to the printing point is superimposed on a calculating machine in which multiplication is performed by the depression of denomination selecting and numeral keys 20 so disposed that they can be directly operated by the tabulating and numeral keys respectively of the typewriting machine. The numeral keys of the calculating machine are only operative in feeding items 25 into the machine to the extent determined by the preliminary depression of a denomination selecting key so that until a tabulating key in the typewriting machine is depressed in order to bring the paper relatively to the printing point into a quantity or price position the calculator is not actuated and then only to the extent determined by the value of the tabulating key which 30 has been depressed. Otherwise the typewriter is available for independent writing in which the numeral keys may be employed. The calculating machine is intended to perform sums such as the cost of any number of articles, the individual 35 price of which is known but it may equally well be constructed to deal in the same way with various measures such as those of weight, length, capacity or the like. The multiplying machine is preferably combined 40 with totalizer mechanism which performs addition or subtraction with the results obtained from that part of the machine in which multiplication is performed. The construction of this calcula-

tor as to the part in which multiplication is performed and as to the part in which addition and subtraction are performed is detailed in the specifications of the present inventor's concurrent applications for United States of America Letters Patent Serial Nos. 343,629 and 343,630, both filed December 9, 1919.

The multiplying machine with or without the totalizer mechanism is so combined with the typewriting machine that the latter may be removed and without alteration or adjustment used in the ordinary way apart from the calculator while on the other hand the calculator may similarly be used for performing sums independently of the typewriter the keys being directly manipulated by the fingers.

In the accompanying drawings which illustrate one construction of the improved calculating machine,

Figure 1 is a front elevation of the machine.

Figure 2 is an elevation of the left hand side of the machine.

Figure 3 is a sectional elevation taken on or about the centre of Figure 1 and showing on an enlarged scale the principal features in the construction of the machine in so far as they relate to the selective mechanism of the multiplying machine and the operation of the adding and subtracting mechanism. In this view parts are omitted and others shown somewhat diagrammatically while the mechanism comprised in the rear portion of the machine is not included. The drawing is arranged generally with the object of illustrating the manner of operating and the relationship between the typewriting machine and the chief features of the multiplying and adding mechanisms described in the specifications of the concurrent patent applications above referred to.

Like letters indicate like parts throughout the drawings.

It may be noted that for convenience in reading the present description and interpreting the drawings in conjunction with the specifications and drawings of the concurrent patent applications wherein the mechanisms and their operation are generally described in more detail than is here necessary, the several parts of those mechanisms which appear in the present draw-

ings are hereinafter referred to by the same letters of reference as have been utilized in referring to those parts in the specifications of the concurrent applications. The capital letters of the alphabet are used to indicate parts in the other specification which describes the part of the calculating machine in which multiplication is performed. On the other hand the small letters of the alphabet are used to indicate those parts which constitute the adding mechanism and are referred to in the other specification describing that mechanism, but in that case the corresponding capital letters of the alphabet are used. The small letters of the alphabet are here employed to prevent confusion with the similarly lettered parts of the multiplying mechanism.

The typewriting machine which is here more particularly described and illustrated by way of example is of the well known Remington type and is provided with a series of letter keys disposed in the fore part of the keyboard, a series of numeral keys arranged behind the letter keys, and a series of tabulating keys placed behind the numeral keys. The tabulating keys operate in a known manner to determine the position of the paper on the carriage relatively to the printing point, and are intended to be employed for example, when typing, a succession of money sums such as occur in a bill or statement of account so that the figures in the several lines may appear in their proper relative positions beneath each other. It may be noted that the calculating machine hereafter described and illustrated in the drawings is constructed so as to enable it to deal with sums involving any number of articles up to 99 at any price from one penny up to £9-19-11. It will be understood however that the machine may be constructed to have a larger capacity or if necessary to deal with other monetary systems or either weights or measures. The limitations in the capacity of the present machine are merely for convenience and the simplification of the construction for purposes of description and illustration.

As will be seen in Figure 1 the typewriting machine is provided with ten tabulating keys A A all of which are not arranged or shown as being operative on the calculating mechanism owing to the limited capacity of the latter. The keys A A which are thus operative are five in number and are respectively marked in the drawing with their values. Thus the key on the extreme left of the row is used to tabulate or position the paper on the carriage for unit pence and unit articles. The next key to the right of it is used for tabulating for tens of pence and tens of articles. The next operative key towards the right is for tabulating for unit shillings and that next to it for tens

of shillings. Finally the fifth operative tabulating key is for dealing with unit pounds.

The numeral keys B B are eleven in number of which ten marked from 1 to 0 running from the left hand side of the machine, form the row immediately in front of the tabulator keys. The eleventh key B B¹ is situated at the extreme right hand end of the row of letter keys which lies in front of the row of numeral keys. This key, which may be referred to as the "ten" key, is specifically marked and together with the 0 key, which is just behind it, is only employed, so far as the calculating mechanism is concerned, when dealing with the prices of articles involving tenpence or elevenpence.

Each tabulating key lever A A' is provided with a downwardly directed projection A A² and each numeral key lever B B' is provided with a similar projection B B² as clearly shown in Figure 2. The provision of the projections A A² and B B² as additions to the existing tabulating and numeral key levers may not be necessary if these levers or any of them are so formed originally, as to operate on the keys of the calculating machine in the desired manner.

The calculating mechanism is operated by two series of keys which correspond to and are actuated by the tabulating and numeral keys of the typewriting machine. There are five denomination selecting keys A respectively corresponding in position and value to the five tabulating keys A A. There are eleven numeral keys B and B⁰ respectively corresponding in position and value to the numeral keys B B and B B¹. The multiplying machine is so constructed that the numeral keys B are only operative to feed items into the machine as and to the extent determined by the preliminary depression of a denomination selecting key A. Hence unless a tabulating key A A has been depressed and by means of it the corresponding denomination selecting key A, the depression of any one of the numeral keys B B has no effect in the calculating mechanism even though the keys B are necessarily depressed by the keys B B. It is thus possible to use freely the numeral keys B B for the purpose of writing matter in respect of which no calculation is required. When however a tabulating key A A has been depressed the numeral keys B of the multiplying machine are thereby rendered "alive" and subsequent depression of any one of them as a result of depressing a typewriter key B B causes actuation of the calculating mechanism.

The value of the tabulating key which is first depressed determines the extent to which the numeral keys are subsequently rendered "alive" so that in accordance with this value, after one or more

numeral keys have been depressed, these keys once more cease to be alive and can then be again freely used without performing calculating functions.

6 The principal parts of the calculating machine may be enumerated as follows:—

1. Selective mechanism controlled and operated by the tabulating keys A A and numeral keys B B through the denomination

10 selecting keys A and numeral keys B.

2. A series of product plates which are positioned by stops set up by the selective mechanism when the keys are depressed to feed any sum into the machine.

15 3. Adding mechanism by means of which the several products are collected and the total resultant product constituting the answer to the multiplication sum that has been performed is presented.

20 4. Totalizing mechanism by means of which the successive total products are added together or by means of which subtraction can be performed with these products.

25 5. Actuating mechanism by means of which after the necessary data has been fed into the machine by depression of the keys the various parts of the whole machine are caused to perform their several functions so as to produce the desired result and present the answer to the multiplication sum and the answer to the addition or subtraction sum which has been performed with the products.

30 The totalizing mechanism referred to under the fourth head above together with the actuating mechanism thereof may be separate and detachable from the mechanism which performs the multiplication so that if not required the latter may be used

35 without the totalizing mechanism which can be removed or need not be provided if it is only necessary to ascertain the simple products.

The mechanism comprised in the multiplying and adding parts of the machine are

40 fully described and illustrated in the specifications of the concurrent patent applications above referred to but their general construction, operation and relation are hereunder referred to and illustrated in the drawings so as to make clear the manner

45 in which the complete machine is operated by means of and in conjunction with a typewriting machine.

50 The principal feature of the selective mechanism is a series of horizontally disposed rods M the longitudinal movement of each of which causes the setting up of a stop O through a plate O² so that the end

55 of the stop serves to position a product plate P. These product plates are conveniently disposed in groups each plate being provided with V-shaped guides by means of

60 which it is positioned by the stops O which may be set up in accordance with the value

represented by the stops. The front ends of the stop-setting rods M are all grouped like a chess-board in rows parallel in two directions and in one plane which plane is at right angles to the plane of the paper 70 in the view of the mechanism shown in Figure 3. A series of knives B⁰ which are vertically disposed side by side face the ends of the stop-setting rods M and each knife by the depression of a numeral key B is 75 reciprocated towards or between the grouped ends of the setting rods M. These ends can be shifted in horizontal rows at right angles to the knives by means of notched plates K so as to bring the ends of 80 all the rods M in any selected row into the paths of the knives B⁰.

Each numeral key and also the key B⁰ is mounted on one arm of a two armed lever B' B² pivoted at B³. The free end of each 85 key lever arm B² is rounded and engages a recess in the end of the arm B' of a two-armed lever pivoted at D⁴. The other arm B⁸ of this lever is pivotally connected to a horizontally extending portion of one of 90 the knives B⁰. The portion of the knife to which the lever B⁸ is connected is forked at B¹⁰ to engage a rod B¹¹ which guides the knife B⁰ so that it will always remain vertical. By means of these lever connections 95 the depression of a numeral key B will cause a knife B⁰ to be moved towards the grouped ends of the stop-setting rods M and will push in the manner described those rods which have been set out into the path of the 100 knife. By means of a similar arrangement of levers operated through a bar B⁴ which lies beneath all the numeral key levers B' and is carried at its ends on two levers B⁵ pivoted on the axis B³ one knife is 105 always reciprocated whenever any one of the numeral keys B or B⁰ is depressed. A bar D carried on two armed levers D' D⁴ pivoted at D⁵ so positioned with relation to the arms B² of the key levers that whenever a numeral key is depressed the lever B² will strike the bar D and move the lever D'. The latter has a second arm D⁴ which extends downwards and serves to operate an escapement hereinafter to be more particularly referred to. 110

The ends of the stop setting rods M are set out into the paths of the knives according to the selection effected by means of a series of cams F² F⁴ arranged in pairs on a 120 vertically disposed rotatable cam shaft F. These cams push laterally the notched plates K which as mentioned carry the ends of the stop setting rods M. Rotation is imparted to the cam shaft F by the movement under 125 spring action of a horizontally disposed bar or plate E termed the differentially actuated member or plate which carries a rack E¹¹ gearing with a toothed wheel F' mounted on the lower end of the cam shaft F. The es. 130

capement already referred to controls the movement of the differentially actuated member and thus also the rotation of the cam shaft and determines the selection and operation of the cams. The ratchet wheel G of this escapement is mounted on the lower end of the cam shaft F.

It is to be noted that certain stops somewhat similar to the stops O are operated by longitudinally moved rods similar to the stop setting rods M but these stops so act that until they are withdrawn by the longitudinal movement of their rods they inhibit the movement of the product plates.

These latter are arranged in two main groups and one inhibiting stop controls all the product plates in one group, those in the other group being similarly controlled.

There are also inhibiting stops for each individual row of stop setting rods M. These inhibiting stops and the rods which operate them are not shown in the drawings of the present case but they are actuated by a knife such as B⁵ into the path of which the ends of these rods can be set out in the same way as the ends of the rods M. The knife which acts on the inhibiting stop rods is actuated by the bar B⁴ which as already described is so positioned that the depression of a key lever imparts movement to the lever B⁵. Hence depression of any number key operates not only the knife B⁵ directly connected thereto but also that knife which acts on the inhibiting stop rods.

Each denomination selecting key A¹ is mounted on one arm A' of a two-armed lever pivoted at A², the other arm of this lever A² being downwardly directed and lying adjacent to the differentially actuated plate E. A rod C carried by two levers C' pivoted on the axis A³ lies against all the levers A² operated by the denomination selecting keys so that whenever one of these keys A¹ is depressed a lever A² moves the lever C' and operates the parts connected thereto. A projection C' from the end of the lever C' engages a pawl H which acts on the escapement wheel G.

The end of the lever D⁴ which is T-shaped engages the two arms J' J² of a pawl which acts on the escapement wheel G. One end of the T-shaped part of the lever D⁴ also acts on a tail H² of the pawl H. A spring not shown in the drawings exerts a constant pull on the differentially actuated plate E tending to move it horizontally towards the right hand part of the machine and when this plate is allowed to move by the action of this spring it imparts rotation to the cam shaft F through the rack E¹ and pinion F'. This movement is permitted to a predetermined extent and in definite steps as a result of the depression of a tabulating key A¹ and a denomination selecting key A² when operated by the numeral keys B¹ B²

and B. On the upper edge of the differentially actuated plate E are a series of projections which correspond to the rotary positions of the cam shaft F as determined by the path of the ratchet wheel G and these positions bear definite relations to the sequence of the operations performed when manipulating the numeral and denomination selecting keys for the purpose of performing a sum with the machine.

The operation of the selective mechanism as the keys of the typewriter machine are manipulated may now be described in general terms.

The first step is to depress a tabulating key A¹ which results as already mentioned in rendering the calculating mechanism alive in consequence of the depression of the corresponding denomination selecting key A¹. The process of rendering the machine alive results from the end of the lever A² acting on the bar C and so lifting the pawl H clear of the ratchet wheel G. Simultaneously the end of the lever A² is thrown into the path of one of the projections on the upper edge of the differentially actuated plate E with the result that though the pawl H has been lifted clear of the ratchet wheel G the cam shaft F can only rotate to the extent permitted by the distance that the plate E is able to move before this movement is checked by a projection on the differentially actuated plate meeting the end of the lever A². Directly the key A¹ is released the end of the lever A² is disengaged from the differentially actuated plate projection but further movement except to a slight extent of the plate E cannot take place owing to the pawl H now engaging one of the teeth of the ratchet wheel G. As already mentioned the product plates are arranged in two groups and the stop setting rods M are similarly grouped where their ends are presented to the knives B⁵. The first group in the present machine comprises the upper rows of stop setting rods and deals with tens of articles at pounds, shillings and pence. The lower rows comprise rows of stop setting rods comprising the second group dealing with unit articles at pounds, shillings and pence. The extent to which the differentially actuated plate E moves and consequently the cam shaft F and ratchet wheel G rotate when a tabulating key is depressed is

in accordance with the value of this key. At this stage of the operations when dealing with such a sum as is intended to be performed by the machine it is only desired to designate the number of articles whose total price is to be ascertained. Consequently the tabulating key which is struck is either for units or tens of articles and the cam shaft rotates accordingly. Owing to this rotation of the cam shaft F certain of the cams F¹ F² have acted on the corresponding

notched plates K and shifted the ends of certain of the stop setting rods M so as to bring them into the paths of the knives B².

In order to write on the paper in the typewriting machine the number of articles in question the necessary numeral keys B B are now depressed. As each of these keys is depressed a knife B⁹ is moved forward against the ends of the stop setting rods M presented to it and these rods are pushed and the corresponding stops O are set up for the positioning of the product plates. At the same time owing to the movement imparted to the lever D' D⁴, through the action of each numeral key lever arm B² on the bar D, movement has been imparted to the pawl J and also to the pawl H through its tail H². In this way further step-by-step rotation of the cam shaft F is permitted until the one or 10 more digits comprising the number of articles in the sum have been written when the ratchet wheel G will have reached a point where it is so engaged by the pawl H that further depression of any of the numeral 15 keys will have no effect on the calculating mechanism until another tabulating key has been depressed. The calculating mechanism has now once more ceased to be alive and as a result it is possible to write other figures 20 with the numeral keys when operating the calculating mechanism. This arrangement is of importance as it enables many forms of bill or statement to be written out by the typewriting machine which involves the use 25 of other figures beyond those actually forming part of the calculation to be performed by the machine. Thus for instance it may be supposed that it is desired to write out such a statement as the following:—17 pieces 30 of carpeting quality 1750 each 3 yards by 6 at £1.7.4. In writing this the machine is only rendered alive by depression of the necessary tabulating key for the tens of articles and after the two digits making up 35 the figure 17 have been typed the machine ceases to be alive and the other numeral keys necessary to write the figures involved in the designation of the material can be employed without effect on the calculating part of the 40 mechanism. Other matter which it may be desired to set down may now be typed freely and it is not until the operator wishes that the calculating machine again becomes alive. It is then necessary to depress the tabulating 45 key corresponding to the first digit of the price according to whether this price is pounds, shillings or pence or any combination thereof.

If the sum representing the price of the 50 articles involves pounds, the corresponding tabulating key A A is depressed which renders the calculating machine alive and depression of the numeral key follows. Since, as already mentioned, the present machine is constructed as shown to deal only with a

price sum involving unit pounds it is only provided with a unit pounds tabulating or selective key A. Obviously, however, the machine may be constructed to deal with large sums when denomination selecting keys 70 A are provided corresponding to all the tabulating keys A A of the typewriting machine which enable the paper on the carriage to be positioned for tens of pounds, hundreds of pounds, and so forth. 75

When the pounds numeral key has been operated the pawls of the escapement are moved and the cam shaft permitted to rotate into a position for dealing with tens of shillings. If the price in question involves tens 80 of shillings then the numeral keys for typing the figure can be depressed and the selective mechanism accordingly operated. If, however, the price comprises only a unit number of shillings it is necessary to depress the 85 unit shilling tabulating key in order to bring the paper into the necessary position and at the same time rotate the cam shaft to the extent necessary to enable unit shillings to be dealt with in the selective mechanism. 90

If the price of the articles is a sum comprising shillings only or shillings and pence but no pounds then at the commencement of this stage of the operation it is necessary to depress either the tens of shillings or unit 95 shillings tabulating key after which the necessary numeral keys are operated. Without further operation of the tabulating keys the mechanism is then in a state for the numerical keys corresponding to the pence to be depressed. 100

The operation of the machine if 10d. or 11d. occurs in the sum to be dealt with is to some extent determined by the numbering and arrangement of the numeral keys of the typewriting machine. In this machine which is more particularly here described and illustrated the eleven keys B B of the typewriting machine as already mentioned are numbered consecutively from 1 to 9, the last key on the right hand side being marked 105 0 or with some special sign. The key B B^x is marked 10 or again with some distinctive sign. If 10d. is to be written the key B B^x is first depressed and then the key B B which is marked 0 while for 11d. the key B B^x is first depressed and then the key B B marked 1. The depression of these keys in this order has the necessary action on the escapement to effect that rotation of the cam shaft which is necessary to operate the selective mechanism so that the proper stop rods may be set up by the knives B². 110

Each of the product plates P is a member 125 so constructed and movable parallel to itself in two directions into positions determinable by the setting up of one or a pair of stops O that the member will indicate a product by its position the amount of these products being ascertained and added by mechanism. 130

which presents the total. Each plate carries a mechanical representation of the products obtainable from that plate in the form of a series of pins the length of which is a measure of the value of a product. When the product plates have been positioned in accordance with the stops set up by the selective mechanism the product values are ascertained by a series of fingers which when released feel the lengths of the product pins presented to them. These measures of lengths are then added together. This adding mechanism comprises several units each of which is composed of a series of pulleys over which passes a flexible tape or the like of which one end is fixed while the other end is connected to a template which can rotate or move into a position determined by the extent to which the tape is pulled or let out by the movement of one or more of the pulleys. In the present calculating machine each movable pulley is connected to a finger by means of which the length of a product pin is felt so that the pulley makes a movement corresponding to the length of the product pin. Thus the value of any product is transferred into the adding unit and the sum of these products in that unit is represented by the positioning of the template. Each of these templates is conveniently formed as a rotatable disc so cut or notched to varying depths as to correspond to the several integers with which the unit has to deal. The depth of the cutting or notches in the template can be ascertained or felt by a finger which in turn positions a number plate or equivalent. Such a template is shown at S' in Figures 2 and 3.

In the drawings accompanying the present specification only one product plate P is shown somewhat diagrammatically in order to indicate its general position in the machine, but the grouping and general operation of these product plates is not shown. The manner in which the products ascertained from the product plates are added in the several adding units is also omitted here but is fully described in the specification of one of the concurrent patent applications above referred to, Serial No. 343,629, filed December 9, 1919.

The finger which feels the path of the notch in each template S' is constituted by the end of one arm U' of a two-armed lever pivoted at c'. The other arm c' of this lever carries a quadrant c' on the face of which is marked successive numbers corresponding to the increments represented by the steps or notches in the template S'. As will be understood there are a series of template S' each with its finger lever U' and quadrant number plate c' and all these quadrant carrying levers c' are normally held in the position indicated in Figure 3 by means of a bar k which runs across the ma-

chine so that the feelers U' cannot engage the templates. When the templates have been positioned in accordance with the product totals the bar S' is moved by the actuating mechanism and the quadrant levers c' are all allowed to drop into the positions determined by the templates S'. The answer to the sum performed in the machine is then exhibited at the windows C C formed in the casing C' which closes in the front of the machine (see Figure 1).

The mechanism of that part of the machine in which multiplication is performed has now been described or generally indicated with the exception of the actuating mechanism, by means of which, after the data for the performance of a sum has been fed into the machine by depression of the keys of the typewriting machine the parts of the calculating machine are caused to perform their several functions which result in presentation of the answer. The main features of the actuating mechanism are shown in Figure 2 at the right hand side of the machine but it will be more convenient to refer to this mechanism in detail later on. It may be said here, however, that the operation of the actuating mechanism can be effected either by means of a hand lever which is rocked or oscillated at the required moment or, as in the machine here illustrated, by means of a rotating wheel or crank which can be coupled to a power driven constantly rotating shaft when the mechanism is to be put into operation.

The calculating machine may be constructed and used in the form so far described, that is to say, this machine may be arranged to perform multiplication only with the data supplied to it. Preferably, however, as in the machine illustrated there is combined with it mechanism for performing addition or subtraction with the products ascertained from the multiplier and this adding mechanism will now be described as regards its principal features and general method of operation. The detail construction of this adding mechanism is however fully described in the specification of my pending application for patent Serial No. 343,630, filed December 9, 1921.

The adding machine is built up of a series of co-operating units each comprising a pair of pivotally mounted concentric sectors one toothed on its concave side and the other toothed on its convex side. A double pinion carrying a numbered wheel is so mounted on a movable member that the pinion can be brought into engagement with either of the sectors, the number wheel being locked against rotation except when the pinion and a sector are engaged. Each pair of sectors can be set or positioned in accordance with the value of an item fed into the machine when the value of a product is ascertained by feeling

one of the templates S' by the finger U' . After being so set the pinion of the corresponding number wheel is brought into engagement with one or other of the sectors according to whether addition or subtraction is to be performed and the sector is then moved back to its zero point, in so doing rotating the number wheel to the extent determined by the original setting of the sector.

The several units which make up the complete machine are disposed side by side in positions opposite the templates S' and so that they can be controlled simultaneously by rock shafts, levers and bars operated by rotating cams which receive motion from the main actuating mechanism of the machine. Certain of these cams are constantly acting but three other cams are provided which can be alternatively clutched to the main shaft for the purpose of actuating the mechanism in accordance with whether the machine is to be used for performing addition or subtraction with the products ascertained and fed into it, or if it is to be cleared, that is to say, if any existing sum which may be set up in it is to be wiped out and the number wheels restored to zero.

The chief features of the mechanism comprised in one of these units will here be described and it is to be understood that the construction of all the units is substantially the same except for such detail differences as are necessary to enable the several units to deal with different values namely, pence, unit shillings, tens of shillings, unit pounds, tens of pounds and so on.

The curved-tooth sectors a and b are both mounted concentrically on the outer part c of one of the quadrant carrying levers, this part of the lever conveniently forming an angle with the part c' adjacent to the shaft c^2 on which the lever can turn. On a horizontal frame member d' is pivoted a lever in the form of a plate e which is inclined from its pivot e' towards the front of the machine.

The free end of this plate e is forked as at e^2 to engage a pin f on the end of a lever f' keyed on a rock shaft f^2 . On a stud e^3 projecting from one side of the plate e is mounted a double pinion g g' . That portion g of this pinion which has the larger diameter has teeth adapted to engage the outer toothed rack a which rack operates for the purpose of performing addition. The smaller part g' of the pinion has teeth adapted to engage the inner rack b which performs the operation of subtraction. Connected to the double pinion g g' is a number wheel having a peripheral flange g^3 which is directed laterally from the plane of the wheel towards the face of the plate e . In the flange g^3 are formed a series of equidistant notches which alternate with num-

bers engraved or otherwise marked on the outer face of the flange. These wheels are so placed that the numbers thereon can be successively presented to and read at windows C C^2 formed in the casing of the machine (see Figure 1).

On a horizontal bar d^2 forming part of the frame of the machine are disposed at intervals according to the positions of the number wheels a series of downwardly directed brackets d^3 each of which carries on the side of the bracket adjacent to the number wheel a lateral projection d^4 . The shape and dimensions of this projection d^4 are such that it can pass freely through any one of the notches in the flange g^3 of the number wheel as this wheel is raised or lowered by the movement of the plate e about its pivot. If the movement of the plate e is checked at a mid-point the projection d^4 will lie in one of the notches and lock the number wheel against rotation.

Adjacent to each bracket d^3 but positioned over the face of each number wheel flange g^3 is a downwardly directed plate which can engage the end of a spring controlled lever which projects through one of the notches in the flange g^3 and is carried by the number wheel. When this lever which constitutes a pawl is in engagement with this plate the number wheel is in its zero position.

As will be understood all the plates e with the number wheels and pinions carried thereon can occupy three distinct positions according to the movement imparted to the ends of these plates by the levers f' when the shaft f^2 is rocked.

The first and what may be called the normal position occupied by each plate e when the parts are in their initial or zero positions and ready for the performance of a calculation is that in which this plate is shown in Figure 3. Here the free end of the plate has been raised to its limit position in which the pinion g is in engagement with the outer toothed sector a . The projection d^4 now lies within the flange g^3 of the number wheel which is therefore free in so far as obstruction by this projection d^4 is concerned to be rotated by the movement of the toothed sector a . In the second or intermediate position the plate e is partially lowered with the result that the pinion g is removed from engagement with the toothed sector a but has not been brought into engagement with the inner toothed sector b . In this position the projection d^4 lies within one of the notches in the number wheel flange and this wheel is thus locked against rotation in whatever position it may have been set. In the third position when the plate e is lowered to its limit the pinion g' is in engagement with the inner toothed sector b . The projection d^4 has now passed

through one of the notches in the number wheel flange and this wheel is again free to be rotated by movement of the sector lever $c c'$ but in a direction opposite to that in which it is rotated when the pinion g is in engagement with the sector a .

It will be seen in Figure 3 that the bar k is not actually in contact with the lever $c c'$ but lies against part of another lever l which is pivotally mounted on the same shaft c^2 as the lever $c c'$. The lever l is connected to the lever $c c'$ in a yielding manner so that movement imparted to the lever l by the bar k is communicated to the lever $c c'$. Normally the limit of the return movement of the lever $c c'$ is fixed by a stop which however when a carry occurs from one unit to another is removed so as to permit a certain over movement of the lever $c c'$ to take place. This over movement is to the extent of one integer. The connection between the levers l and $c c'$ allows this over movement to take place but when the stop prevents this over movement of the lever $c c'$ the connection between the levers yields and permits the necessary full movement to be imparted to the lever l by the bar k .

Details of the mechanism by means of which a carry is effected from one unit of the adding mechanism to the next need not be here described as they are fully set forth in the specification of the companion application describing the adding mechanism.

The manner in which the principal parts of this mechanism act when performing addition or subtraction may now be briefly described. It is to be noted that the mechanism does not commence operations until the main actuating mechanism is set in motion.

When addition is to be performed the first result of putting the actuating mechanism into operation is to rock the shaft f^2 so as to lower the plate e from its first or upper position into its second or intermediate position. This moves the pinion g out of engagement with the outer toothed sector a and locks the number wheel by engaging the projection d^4 with that notch in the number wheel flange which is presented to it. At this stage the carry mechanism is reset if it happens to have been employed in performing the previous operation. The sector levers $c c'$ have so far all been retained in their raised and zero positions by the action of the bar k . The bar k now moves away and all the sector levers $c c'$ are allowed to turn on the shaft c^2 and fall towards the front of the machine to the extents determined by the falling of the templates S' by the fingers U' . The shaft f^2 is now once more rocked so as to raise the plate e until the pinion g is again in engagement with the outer toothed sector a .

Finally the bar k once more lifts all the sector levers $c c'$ moving them back again to their zero positions. As each of these levers moves it causes rotation through the pinion g of the corresponding number wheel so that this wheel has now been rotated the same number of integers as the sector had previously been allowed to fall by its template S' and assuming that no carry has taken place into that unit mechanism. If a carry has occurred then the sector receives an over movement to the extent of one integer and the number wheel is rotated to a corresponding further extent. The answer is thus presented at the windows $C C^2$ and can be read off.

When subtraction is to be performed the initial operation of the actuating mechanism is the same as in the case of addition namely the shaft f^2 is rocked and the plate e is lowered from its first or upper position into its intermediate position. By the removal of the bar k the sector levers $c c'$ are now permitted to fall into the positions determined by their templates. The shaft f^2 is then once more rocked so as to lower the plate e still further and bring the pinion g into engagement with the inner toothed sector b . The bar k is now moved back again so as to raise the sector levers $c c'$ and return them to their zero positions in so doing causing the rotation of the number wheels but as will be noted this rotation takes place in a direction which is the reverse of that which occurs when addition is being performed. Here also if a carry is to be effected it is brought about in the same way as when performing addition by means of an over movement past the zero position of each sector lever $c c'$. Finally when the sectors have been returned the plate e is moved up so as to bring the pinion g once more into engagement with the outer sector a when the numbers on the wheels can be read off.

Provision is made for returning all the number wheels to zero so as to clear the machine in order to start a fresh series of operations. This clearing is effected in the following manner and is brought about by suitable manipulation of the actuating mechanism. In the first place by rocking the shaft f^2 the plate e is lowered into its intermediate position and while in this position all the carry levers are reset. Next the plate e is raised so as to bring the pinion g into engagement with the outer sector a . The bar k now moves away so as to release the sector levers $c c'$ which all fall forward and in so doing rotate their several pinions g and number wheels, the extent to which each of the sector levers can move in this case is determined by a pawl or detent lever which as mentioned above is carried by each number wheel and projecting through a

notch in its flange is adapted to engage a plate carried by the bracket d^3 . This prevents further rotation of the number wheel when it has reached its zero position. The 5 plate e is now again lowered into its intermediate position and all the sector levers $c c'$ are raised to their zero positions by the bar k . As will be noted the return movement of the sectors in this case has no effect on the number wheels. When the sectors and the number quadrants c^3 are all in their zero positions the plate e is again raised so as to bring the pinion g once more into engagement with the sector a . Thus 10 at the end of the cycle the parts are in their respective positions in readiness for the commencement of a new operation, all the number wheels together with all the number quadrants c^3 being at zero.

20. The actuating mechanism by means of which parts of the calculating machine are caused to perform their several functions may now be described in general terms. The 25 details of this mechanism are clearly set forth in the specifications of the concurrent patent applications already referred to.

It may be remarked that the actuating mechanism here described and as shown in Figure 2 of the drawings is intended to be 30 operated by power but the operation may equally well be brought about by a hand lever. A pulley wheel x is provided this wheel being constantly rotated through belting or otherwise by some source of 35 power such as an electromotor, not shown in the drawings. By depressing the key lever z clutch mechanism on the shaft on which the pulley x is mounted is thrown into operation so that this pulley is now connected to the actuating mechanism and begins to operate it. This clutch mechanism is fully illustrated and described in my co-pending application Serial No. 343,630, filed December 9, 1919. This clutch mechanism is conveniently so arranged that it 40 is automatically thrown out of engagement when the actuating mechanism has performed half of its complete cycle. At this stage, the products of the multiplication 45 sum, to be performed in the multiplier are presented in the form of an answer at the windows $C C'$. By stopping the movements of the mechanism at this stage in the cycle it is possible to read these figures. By 50 again depressing the lever z the mechanism is once more connected to the source of power and the cycle is completed when the answer to the sum performed in the adding part 55 of the mechanism is presented at the windows $C C'$.

When the clutch connection is in operation rotation of the pulley wheel x brings about rotation of the wheel t^5 through gearing which comprises a wheel t^8 gearing with 60 a pinion, which is not shown, mounted on

a shaft co-axial with the pulley wheel x , and a pinion t^6 on the same shaft as the wheel t^8 which pinion t^6 gears with the wheel t^5 . The cams, which as already mentioned cause the various parts of the adding mechanism to perform their several functions, including those cams which can be alternatively thrown into action according as the machine is to perform addition or subtraction or to be cleared, are mounted 70 on the same shaft as the gear wheel t^5 . The addition, subtraction and clearing cams are respectively thrown into operation by movement of a lever the end of which t^2 projects through an opening in the casing 80 $C C'$ this lever being capable of being locked in each of the three positions which it can occupy. Hence when the lever t^2 has been set rotation of the wheel t^5 causes the desired 85 cycle of movements in the adding mechanism to commence.

From a stud which constitutes a crank pin on the outer face of the gear wheel t^5 runs a connecting rod $V V$ the other end of which is pivotally connected to a lever V^2 keyed on a shaft V' . The lever V^2 is in the form of a plate which carries certain sectors or cams V^3 , V^4 , and V^5 and laterally projecting pins V^6 and V^7 . Part of the pin V^6 may be conveniently employed as the point of connection of the connecting rod $V V$. As the wheel t^5 rotates the lever V^2 is rocked towards the front of the machine and in the course of its movement 90 these sectors or cams and pins act in determined order and manner on various levers suitably disposed for example the lever W pivoted at W' the lever Y pivoted at Y^2 and the lever X pivoted at X^2 . These levers 95 act on certain portions of the mechanism 100 of the multiplier and cause them to perform their respective function in the required order as the lever V^2 is rocked in one direction and then in the other. The 105 operation of this actuating mechanism is 110 fully and clearly described in my specification of the concurrent application Serial No. 343,629, filed December 9, 1919, in which the construction of the multiplier is set forth and it is therefore unnecessary to include it here.

As will be seen from Figures 1 and 2 the typewriting machine stands on the legs or studs $D D$ with which these machines are usually provided these legs resting on a plate $E E$ disposed on the top of the calculating machine. The typewriting machine need not be permanently connected to the calculating machine but is preferably left 115 so that it can readily be lifted off the calculator. Thus the typewriting machine can at any time be removed and used in the ordinary way apart from the calculator. Similarly when the typewriting machine 120 has been removed the calculating machine 125 130

could be used separately for performing calculation the denomination selecting keys A and numeral keys B being preferably so formed that they can be operated by pressure from the fingers in the same way as the keys of a typewriting machine. It is thus apparent that while the two machines are distinct and can be used separately for their several purposes it is possible by mere superposition of the typewriting machine on the calculating machine to enable the calculator to be operated conjointly with the typewriting machine and by direct manipulation only of the ordinary keys of the latter. It will be seen that it is possible to thus employ in conjunction with the calculating machine a known form of typewriting machine without any alteration being necessary in the latter except the provision or projections such as A A² and B B² on the typewriter key levers so that depressions of any one of these key levers will bring about depression of the corresponding keys A and B of the calculating machine. Even these slight alterations may not be necessary in some cases if the key levers of the typewriter are so formed as to act as desired on the keys of the calculator. Obviously the disposition of the calculating machine keys A and B must be such as to properly fit and cooperate with the keys of that make of typewriting machine with which it is to be used but the disposition of the keys of the calculating machine can be adapted to various makes of typewriting machine.

Though the two machines are preferably separable in the manner described it will be apparent that they may be permanently connected if desired or some means may be provided for locking the two machines together in a manner which will permit them to be separated should occasion require.

Many details of construction in the whole machine may be varied to meet requirements and the particular purpose for which the machine is to be used. Also the manner in which power is applied thereto for operating the actuating mechanism may be varied as found desirable and convenient.

What I claim as the invention of EDWARD RUSSELL-CLARKE deceased and desire to secure by Letters Patent is:—

1. In a calculating machine the combination of mechanism for performing multiplication, denomination selecting and numeral keys which actuate this mechanism the numeral keys being operative only to feed items into the machine as and to the

extent determined by the actuation of a denomination selecting key, a typewriting machine having tabulating and number keys, and means by which when the typewriting machine is positioned on the calculating machine the denomination selecting and numeral keys of the latter will be respectively operated by the tabulating and number keys of the typewriting machine so that as the tabulating keys when operated determine the position of the paper in the typewriting machine relatively to the printing point so will the denomination selecting keys of the calculator which are simultaneously actuated determine the operation of the calculator as set forth.

2. In a calculating machine the combination of a typewriting machine having tabulating and numeral keys the former being operative to bring the paper relatively to the printing point into a quantity or price position, mechanism for performing multiplication, denomination selecting and numeral keys which actuate this mechanism the numeral keys being operative only to feed items into the machine as and to the extent determined by the actuation of a denomination selecting key, these keys being positioned so that actuation of a tabulating key in the typewriting machine will cause movement of a denomination selecting key in the calculating machine and actuation of a numeral key in the typewriting machine will cause movement of a numeral key in the tabulating machine.

3. In a calculating machine the combination of mechanism for performing multiplication, denomination selecting and numeral keys which actuate this mechanism, mechanism controlled by the denomination selecting keys by means of which the calculating mechanism is rendered "alive" and capable of being operated by the numeral keys, a typewriting machine having tabulating and numeral keys and adapted to be placed on the calculating machine so that the tabulating keys of the typewriting machine will respectively actuate the denomination selecting keys of the calculating machine while the numeral keys of the typewriting machine will respectively actuate the numeral keys of the calculating machine, and totalizing mechanism actuated by the calculating machine as set forth.

In testimony whereof I have signed my name to this specification.

FRANCES MAUD RUSSELL-CLARKE,
Sole Executrix of Edward Russell-Clarke, Deceased.
